UNITED STATES PATENT OFFICE.

JOHN HENRY CLIFT, OF FREDONIA, KENTUCKY.

HAYFORK SIGNALING DEVICE.

Application filed September 22, 1925. Serial No. 57,896.

To all whom it may concern:

Be it known that I, JOHN H. CLIFT, a citizen of the United States, residing at Fredonia, in the county of Caldwell and State of Kentucky, have invented certain new and useful Improvements in Hayfork Signaling Devices, of which the following is a specification, reference being had therein to the accompanying drawings.

10 This invention relates to a hay fork signaling device, and the object of the invention is the provision of simple and efficient means to indicate to the driver who drives the team, or to the engineer controlling the engine that pulls the hay up into the barn, when to return for reloading the fork with hay. The signaling is to be accomplished at the time of tripping the fork, to dump the same in the hay mow, 20 or on a stack.

Heretofore, the only way of giving this signaling was for the man on the load to call to the man on the other side of the barn when he wanted him to stop and return again for another draft of hay, whereas with my invention the bell rings and gives the signal with the tripping of the fork.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is a view in elevation of a hay fork showing my invention applied thereto.

Figure 2 is a perspective view of the striking device used in the embodiment shown in Figure 1.

Figure 3 is a fragmentary view in elevation of a hay fork showing another embodiment of my invention.

Figure 4 is an enlarged fragmentary perspective view of one of the trip levers, showing the striking device, in perspective, illustrated in Figure 3, while

Figure 5 is a longitudinal, vertical sectional view of the same.

Figure 6 is an enlarged view, partly in elevation and partly in section of the bell device shown in Figure 3.

Referring to the drawings by numerals, 55 1 designates the frame in Figures 1 and 3, to which is suitably attached the cross

bar 2. An eye 3 is formed on the central portion of frame 1, through which is passed the suspending cable or rope 4. On frame 1 are pivotally mounted, at 5, the trip levers 6—6. To the inner ends of these trip levers are attached the ends of the ordinary cables 7.

Referring to the embodiment shown in Figures 1 and 2:

The bell 8 is supported upon stem 9, which stem is passed through an apertured portion 10 on bar 2, and the bell is adjustably mounted to a nicely by reason of being held in an adjusted position through set-screw 11; it will be obvious that the operator can adjust the bell 8 upwardly or downwardly, after first loosening set-screw 11, and then by tightening the set-screw, the bell will be held in the desired adjusted position. The striking device 12 includes a curved plate 13 and striker 14; this plate 13 is curved to conform to the curved inner face of the trip lever to which the striking device is attached. When the cable 80 is pulled by the operator this causes the trip levers to move downwardly, resulting in the striking device striking the bell 8 and sounding the signal or alarm, whereupon the person having charge of the team 85 that is lifting the load, or the engineer in charge of the engine will be warned to stop immediately the further lifting of the hay fork. Then the operator of the team or the engine can lower the hay fork for a 90 new load.

Referring to the embodiments shown in Figures 3 to 6:

The bell 8 is suspended from a hinged stem 15 (Fig. 6) which stem is threaded 95 into eye 3, for adjustment purposes, whereas in the embodiment in Figure 1 the stem 9 is adjusted in the enlarged portion 10 and held in the adjusted position by set-screw 11. The parts of the stem 15 are hingedly connected together by pivot pin 16. The striking device 14^a, in this embodiment, includes the curved plate 17 with the striker 18, and this plate is provided with an elongated slot 19, in which is positioned the screw 20, so that the striking device 14^a can be adjusted accurately upon the curved face of the trip lever to which it is secured, whereby when the trip lever is held down by the cable 7 to permit the load to be dumped, the striker 18 will strike against the bell 8 giving the desired signal. By reason of 100 105 110

the bell 8 being pivotally mounted at 16 upon the eye 3, said bell will yield or give by means of a swinging action, so that it will not be injured if the adjustment of the 5 striking device is not accurate or if for some reason the striking device worked loose upon the screw 20.

In the embodiment shown in the drawings, it will be seen that the necessary combination includes a frame, a bell adjustably mounted on said frame, a trip lever, and means carried by the trip lever for actuating the bell for sounding a signal.

While I have described the preferred embodiments of my invention and have illustrated the same in the accompanying drawings, certain minor changes or alterations may appear to one skilled in the art to which this invention relates, during the extensive manufacture of the same, and I, therefore, reserve the right to make such alterations or changes as shall fairly fall within the scope of the appended claims.

What I claim is:

25 1. In a hay fork signaling device, the combination with a frame, of a bell on said frame, a trip lever on said frame and adapted to move towards and away from said bell, and a striking device provided with 30 a curved plate fitting snug against the trip lever for striking said bell when the trip lever is moved towards said bell.

2. In a hay fork signalling device, the combination of a frame, a vertically adjustable bell carried by said frame, a pivotally mounted trip lever on said frame and adapted to swing close to said bell, and a striking device secured to said trip lever and adapted to strike said bell when said trip lever 40 is swung towards the bell.

3. In a hay fork signaling device, the combination of a frame, an adjustable and a swinging bell carried by said frame, a trip lever carried by said frame and adapted to move towards and away from said bell, an 45 adjustable striking device attached to said

trip lever and adapted to strike said bell when said trip lever is moved towards the bell.

4. In a hay fork signalling device, the combination of a frame, a bell provided with a sectional stem hingedly connected together said stem adjustably carried by said frame, a trip lever pivotally mounted on said frame and adapted to swing close to said bell, a 55 striking device including a curved plate provided with a striker, said plate provided with an elongated slot, and a screw in said slot and threaded into said trip lever for holding the striking device in an accurate adjusted position for striking the bell when the trip lever is swung close to the bell.

5. In a hay fork signaling device, the combination of a frame provided with an eye, a trip lever pivotally mounted on the 65 side of said frame and adapted to move towards the center of the frame, a two section stem hingedly connected together and threaded into said eye, a bell supported upon the lower end of said stem, a striker 70 device including a curved plate and a striker on one edge of said trip lever, said plate provided with an elongated slot, and a screw in said slot and threaded into said trip lever whereby the striker device is adjusted 75 to a nicety with respect to the bell for striking the bell when the trip lever is swung upon the frame.

6. In a hay fork signaling device, the combination with a frame, of signaling 80 means mounted on said frame, a trip lever pivotally mounted on said frame, signal operating means mounted on said trip lever and adapted to operate said signaling means when the trip lever is pivoted on said frame 85 to release a load, and means connected to said trip lever for pivoting the same to a load-releasing position.

In testimony whereof I hereunto affix my signature.

JOHN HENRY CLIFT.
